H. Trumbull,

Broom Head,

No 56,640.

Patented July 24, 1866.

Fig. 1.

Fig. 2.

UNITED STATES PATENT OFFICE.

HARVEY TRUMBULL, OF CENTRAL COLLEGE, OHIO.

IMPROVED BROOM-HEAD.

Specification forming part of Letters Patent No. 56,640, dated July 24, 1866.

To all whom it may concern:

Be it known that I, HARVEY TRUMBULL, of Central College, in the State of Ohio, have invented certain new and useful Improvements in Broom-Heads; and I hereby declare that the following is a true, full, and exact description of the same, reference being had to the accompanying drawings, and to the letters of reference contained therein.

The nature of my invention consists in certain mechanical devices for holding broom-corn in position.

In the drawings annexed, Figure 1 represents a plan view of my broom. Fig. 2 is a plan view of the clamp for holding the broom-corn.

The letter A, Fig. 2, represents the lower jaw of the clamp, and is made solid with the screw b. The jaw A has a flange at each end, extending upward, for the purpose of receiving corresponding flanges on the upper jaw, C. The jaws A and C form the clamp, as seen in Fig. 2.

The jaw C has a hole through its center sufficiently large to admit of the screw b, when inserted in said hole, to play freely.

Immediately above the jaw C is the nut d, which works on the screw b, and is designed to press down on jaw C and hold it firmly in

position after the heads of the broom-corn have been inserted between C and A.

Above the nut d is placed the ferrule or metal band E. The ferrule E is made solid at bottom, with a hole in its center, into which the screw b is made to work. The screw b extends upward about half the length of the ferrule E, and the lower end of the broom-handle, being inserted in it, is screwed downward until it rests against the bottom of E.

It will be seen that when the ends of the broom-corn are placed between the jaws A and C, the nut d screwed downward so as to press against jaw C, and the ferrule E screwed down to nut d, the ends of the broom-corn will be so compressed that the hardest usage cannot remove them.

Having thus described my invention, what I claim, and desire to secure by Letters Patent, is—

The jaws A and C, the screw b, the nut d, and ferrule E, the whole arranged and constructed in the manner and for the purpose substantially as herein described.

H. TRUMBULL.
